ATTORNEY

UNITED STATES PATENT OFFICE.

AUGUST SUNDH, OF HASTINGS-UPON-HUDSON, NEW YORK.

GATE-HINGE.

1,237,836.

Specification of Letters Patent. Patented Aug. 21, 1917.

Application filed January 11, 1915. Serial No. 1,528.

To all whom it may concern:

Be it known that I, AUGUST SUNDH, a citizen of the United States, and resident of Hastings-upon-Hudson, in the county of 5 Westchester and State of New York, have invented certain new and useful Gate-Hinges, of which the following is a specification.

My invention relates to improved means for rigidly uniting two members, and as 10 herein shown comprises a hinge combined with and forming part of a supporting structure such as a fence to which a gate or the like is connected through the hinge.

It is a common practice to connect a gate 15 post and fence railing together by an ordinary iron T or elbow or other means independent of the gate hinge and to provide a separate fastening device for connecting the hinge to the side or top of the post. An 20 object of my invention is to provide a practical form of hinge in which the stationary hinge member is utilized to rigidly connect the fence rail and the post to which the gate is hinged, thereby simplifying the construction, reducing the cost of installation, and 25 dispensing with the usual fastening devices connecting the gate hinge and post.

Other features and advantages will appear hereinafter.

30 The present invention is a modification of the invention disclosed in Patent No. 1,155,452, granted to me October 5, 1915. The present application also discloses certain features shown in my co-pending application Serial No. 1,529, filed January 11, 1915.

In the accompanying drawings, Figure 1 is an elevation view showing a gate and fence constructed in accordance with the principles of my invention. Fig. 2 is a sectional elevation view showing on a larger scale the upper gate hinge and associated parts. Fig. 3 is a sectional view as indicated by the line 3—3 on Fig. 2. Figure 4 is a fragmentary sectional elevation view of a modification.

The gate 1 is connected by means of an upper hinge 2 and lower hinge or strap 3 to the post 4 of a fence which also comprises 50 an upper rail 5, a lower rail 6 and open wire work 7. The hinge 2 as herein shown is of the automatic gravity operated type and its construction and operation may be the same as fully disclosed in the patent above referred to, and will only be described briefly herein. It is to be understood, however, that

the form of hinge might be widely modified within the scope of the present invention.

The hinge 2 comprises a lower stationary section or member 8, and a swinging section 60 consisting of a bearing member or cam 9, a pintle 10, and a cap 11 connected through an integral bracket 12 to the gate 1. The cam 9 has downwardly inclined diverging cam faces to run on an anti-friction roller 65 13 journaled on a stud in the stationary section 8, so that when the gate is swung in either direction from its closed position, the cam rides up on said roller and lifts the gate. When the gate is released it automatically 70 swings to closed position by gravity. The stationary section 8 preferably forms a chamber to contain a lubricating oil 14 in which the co-operating bearing surfaces are immersed. The section 8 is also provided 75 with an inner tube 15 forming a bearing in which the pintle 10 fixed to the cam 9, has a combined reciprocating and rotary movement.

The hinge section 8 seats on top of the 80 tubular iron gate post 4, and is formed with an extension 16 which projects downward within the post. The extension 16 provides an extended bearing for the pintle 10 which projects downward within the post, and also 85 provides a suitable means for connecting the stationary hinge member and post. To form a rigid and secure connection between the post and stationary hinge member, the extension 16 is formed with integral ribs 17 90 which extend vertically within the post and are of sufficient depth to spring the walls of the post outwardly at the lines of contact with said ribs. The post when made of resilient material is thus placed under a permanent tension, owing to its resiliency, which securely grips the hinge member. It 95 will be seen that by making the ribs 17 of a sufficient depth to slightly distort the post or increase its diameters at the lines of contact with the ribs, a very rigid and secure connection is effected, whether the post is made of wrought iron, steel or other metal.

The section 8 is rigidly connected to the upper tubular rail or runner 5 by means of 105 an integral plug 18 having a close fit in the end of the rail and a bolt or rivet 19 extending through the rail and said plug. The lower hinge 3 may be in the form of a strap riveted to the gate and surrounding the post 110 4 and free to slide up and down on the post as the gate swings.

Fig. 4 illustrates a modification of the connecting means between the hinge section 8 and the fence. In this construction, the connecting piece 18 is in the form of a nipple 5 threaded either internally or externally to be secured to the correspondingly threaded end of the rail 5. A similar connection is provided between the section 8 and the post 4, the latter being threaded to connect with 10 the threaded nipple 20 formed on the section 8. The section 8 may be provided with an integral perforated lug 21 forming a means for connecting the wire work 7 directly to said section.

15 Modifications other than these herein pointed out may be resorted to within the scope of my invention.

What I claim as new and desire to secure by Letters Patent of the United States is,—

20 1. The combination, with a hollow member, of a second member having a projection extending into the hollow member, ribs on said projection which extend longitudinally along the inner surface of the wall of said 25 hollow member, the thickness of said wall being only a fractional part of the interior diameter of the hollow member, and permitting the hollow member to be sprung by

said ribs, said ribs being of sufficient depth to slightly spring the hollow member and thereby form a firm connection between said members. 30

2. The combination with a hollow member, of a second member extending laterally therefrom, and a uniting member rigidly 35 connected to said second member, said uniting member having a projection extending into the hollow member, ribs on said projection which extend longitudinally along the inner surface of the wall of said hollow member, the thickness of said wall being only a fractional part of the interior diameter of the hollow member and permitting the hollow member to be sprung by said ribs, 40 said ribs being of sufficient depth to slightly spring the hollow member and form a firm connection between the hollow member and the uniting member. 45

Signed at New York city, in the county of New York and State of New York, this 50 8th day of January, A. D. 1915.

AUGUST SUNDH.
